UNITED STATES PATENT OFFICE.

FRANK E. CASE, OF CANTON, OHIO, ASSIGNOR TO THE HARVARD COMPANY, OF CANTON, OHIO, A CORPORATION OF OHIO.

DENTAL CHAIR.

No. 910,387.

Specification of Letters Patent.

Patented Jan. 19, 1909.

Application filed June 25, 1906. Serial No. 323,213.

To all whom it may concern.

Be it known that I, FRANK E. CASE, a citizen of the United States, residing at Canton, in the county of Stark and State of Ohio, have invented a new and useful Improvement in Dental Chairs, of which the following is a specification.

The invention relates to chairs of the kind generally used by dentists, surgeons, barbers and others, wherein the back and other parts are adjustable with reference to the seat, so that the body and legs of the patient or other occupant of the chair can be transposed from an erect to a reclining position. 10 In such chairs it is desirable to connect the back, with the headrest thereon, to the seat in such a manner that when the back is adjusted to accommodate the various positions of the occupant, the headrest will 15 travel substantially in the locus of the occupant's head, so that it will not be necessary for the occupant to shift his position on the seat to preserve the position of his head upon the rest. This object is attained by 20 joining the back to the seat by a slidable connection formed on the arc of a circle having its center located over the seat approximately in the position of the hip joint of the occupant. 25 Other features of invention relate to the adjustment of the back on its supporting shank; and the use of a substitute or secondary seat for children, who are not large enough to occupy the ordinary seat. 30 These several objects are attained by the construction, mechanism and arrangement illustrated in the accompanying drawings, in which—

Figure 1 is a side elevation of the chair 40 seat and other upper parts, showing the back-bracket partly in section; Fig. 2, a cross section of the back-bracket and the shank - slide therein, on line 2—2, Fig. 1; Fig. 3, a vertical median-line section of the back, its bracket and the adjoining part of the seat; Fig. 4, a perspective right-rear view of the upper part of the chair, with the ordinary seat proper removed and the secondary seat in position for use; Fig. 5, 45 a detached perspective view showing details of the secondary seat with its parts separated; Fig. 6, a fragmentary view showing the back-shank locking device; Fig. 7, a similar view showing the wedge-block re- 50 moved from its socket; Fig. 8, a fragmentary

section on lines 8—8, Fig. 6, showing the wedge-block in its socket; Fig. 9, a side view of the lower part of the back-shank; Fig. 10, a detached perspective view of the shank-latch showing its parts separated; Fig. 11, 60 a detached perspective view of the head-rest shank; Fig. 12, a fragmentary vertical section showing the method of locking the head-rest shank to the back-slide; Fig. 13, 65 a cross-section on line 13—13, Fig. 12; and Fig. 14, a detached perspective view of the back-adjusting rack.

Similar numerals refer to similar parts throughout the drawings.

In the seat-frame 1 is provided the back-bracket 2 in which is formed the T-shaped slide-channel 3 opening downward and extending longitudinally backward and upward along the arc of a circle having its center, as at 4, well forward and over the 70 seat cushion. The small longitudinal groove 5 is preferably provided in bottom of the slide-channel and when used terminates at a point, as at 6, adjacent to the rear end of the channel. When only one back-bracket 75 is provided, the same is preferably located in the median line of the seat-frame.

The lower end of the back-shank 7 is curved downward and forward and is formed T-shape in cross-section so as to neatly fit 85 and slide longitudinally in the channel of the back-bracket. The ordinary spring latch 8 is provided in the shank-slide and its forward end is adapted to normally enter and operate in the channel-groove 5, and to be 90 stopped at the upper end 6 thereof, whereby the upward movement of the slide can be limited; but by pulling the latch out of the groove, the slide is free to be removed from or entered in the channel as may be desired. 95

The back-shank is locked at any desired position in the back-bracket by means of the wedge-block 9 located in the similar recess 10 in one side of the concave face of the shank-slide, which block is adapted to be forced 100 toward the adjoining wall of the slide-channel by the screw 11 having the handle 12 located to be conveniently accessible to the operator of the chair. The wedge-block may be held in proximate position by the rivet 13 105 passed through the cone-shaped apertures 14 and 14' in the block and slide, the shank of the rivet being slightly smaller than the adjoining small ends of the apertures, and the heads being considerably smaller than the 110

enlarged parts of the apertures, thereby permitting the slight movement required of the block. By means of the slideable connection on the arc of a circle thus described, when the back is adjusted rearward it is also carried slightly downward and accommodates itself to the normal movement of the back of the occupant of the chair in reclining backward; and this is accomplished without the use of 10 pivots at the sides of the chair.

The back proper 15 is pivoted at the upper end of the slide 16, as at 17, and this slide is adapted to be retained and to operate longitudinally in the channel 18 in the back-shank, 15 whereby the back can be adjusted up and down. The back may be locked at any desired point of adjustment by means of the handled screw 19 in the slide, which screw is provided with the annular shoulder 20 adapted to bear against the friction-block 21 and the end 22 of the screw is adapted to operate in the groove 23 in the bottom of the shank channel and to be stopped against the upper end 24 of this groove, which stop normally 20 limits the upward adjustment of the back, and its downward adjustment is limited by the stopping of the lower end 25 of the slide against the shoulder 26 on the back-shank. The back-slide is locked in any desired position of adjustment by turning the handled-screw against the friction-block and forcing the same against the bottom of the back-shank channel on each side of the groove, and the slide can be freely removed from the 25 shank by turning the screw outward far enough to free its inner end from the bottom of the shank above the groove therein. The back is also adjusted on its pivot by means of the pendent rack 27 preferably located in the crotch of the yoke 28 and the 30 detent 29. The yoke is preferably mounted on the same pivot 17, which connects the back proper with its slide, and hangs down against the forward face of the back-shank, by which 35 arrangement the rack is free to go up and down with the slide in its various adjustments. The detent is pivoted to the back proper adjacent to the rack, and by entering it into the various notches of the rack the 40 back proper is held at various points of rotation on its pivot. The extension or tail 30 is provided on the lower end of the yoke of sufficient length to bear against the forward face of the back-shank when the slide is adjusted upward to the limit of its movement; and this tail may be curved forward at its lower end 31, so as to be moved forward by and deflected in front of the rounded upper end 32 of the seat bracket, when the back, 45 the slide and the shank are lowered toward the limit of their movement. This deflection of the tail of the yoke has the effect of tilting the lower part of the back proper forward when its shank is adjusted downward

and forward in the channel of the seat 65 bracket.

The head-rest 33 is formed or attached on the upper end of the shank 34 which in turn is located, longitudinally adjusted and locked in the channel 35 in the rear side of 70 the back-slide in the same manner that the back-slide is located, adjusted and locked in the similar channel of the back-shank.

The frame 53 of the secondary seat is pivotally connected to the frame 1 of the 75 ordinary seat by means of the parallel connecting bars 54 and 55, one of which is located at each end of the seat and respectively near the rear and forward sides thereof. The upper end of the forward bars are preferably provided with the handles 56 by means of which the secondary seat may be raised on its pivotal connections from its normal prone position, as indicated by broken lines in Fig. 4, to its position for 80 use as shown by full lines in the same figure.

The frame 1 of the ordinary seat is preferably filled in by suitable plates as 57 and 58 so as to provide a suitable foot rest for a child using the secondary seat, and the 90 secondary seat may be held in its raised position by means of the brace links 59 which are pivoted together with the upper ends of the rear connecting bars 54 to the seat frame, and at the lower free end are 95 provided with the notches 60, which notches are adapted to engage over the shanks of the headed pins 61 on the lower parts of the forward connecting bars 55, when the secondary seat is raised to its position for 100 use. To lower the seat it is only necessary to disengage these notches from the pins, whereupon the seat is free to be moved forward and downward on its pivotal connections. The secondary seat thus lowered 105 is normally nested under and covered by the ordinary seat cushion of the chair, which same is removed when the secondary seat is to be used.

A convenient manner of making the 110 secondary seat is to connect the upper parts of the forward connecting bars 55 with the pivotal rod 62, and to provide the half journal bearings 63 in the upper side of the seat frame 53, in which bearings the 115 rod is adapted to be located, after which the cushion-plate 64 is riveted on the upper side of the frame thus holding the pivotal rod in its bearing. And the upper ends of the rear connecting bar and the brace links 120 may be connected to the frame on pivot hubs as 65 provided thereon and to be held in position by screws as 66 with an intervening washer 67, which details are illustrated in Fig. 5 wherein the different parts of the 125 secondary seat are shown separated. The secondary seat, when raised, is located adjacent to the back of the chair, so that a

child sitting on the seat can lean against the back, which may be adjusted to and from the seat as may be desired.

The secondary seat shown and described, but not claimed herein, is made the subject-matter of a divisional application which has matured in Letters Patent, No. 891,762, dated June 23, 1908.

What I claim as my invention, and desire to secure by Letters Patent, is—

1. In a chair, a seat frame having a rearwardly extending bracket, a shank having an endwise slidable connection with the bracket, a back having a pivotal connection 15 on the shank, and a curved extension on the back normally resting against the shank and adapted to be deflected by the seat-bracket when the back is lowered toward the seat-frame.
2. In a chair, a seat frame with a cushion thereon and having a channel therein curved on the arc of a circle having its center located over the seat cushion approximately in the position of the hip joint of an occupant, a back with a head rest thereon and having a curved shank adapted to operate in the channel whereby the head rest travels substantially in the locus of the occupant's head, and means for locking the shank 50 in the channel.
3. In a chair, a seat, a back with a head rest thereon, a slidable connection between the seat and the back comprising a channel on the one curved on the arc of a circle having its center located over the seat ap-

proximately in the position of the hip joint of an occupant, a curved shank on the other adapted to operate endwise in the channel whereby the head rest travels substantially in the locus of the occupant's 40 head, and means for locking the shank in the channel.

4. In a chair, a seat frame with a cushion thereon and having a channel therein curved on the arc of a circle having its center located over the seat cushion approximately 45 in the position of the hip joint of an occupant, and a back with a head rest thereon having a curved shank adapted to operate in the channel whereby the head rest travels substantially in the locus of the occupant's 50 head.

5. In a chair, a seat, a back with a head rest thereon, and a slidable connection between the seat and the back comprising a 55 channel on the one curved on the arc of a circle having its center located over the seat approximately in the position of the hip joint of an occupant, and a curved shank on the other adapted to operate endwise in the 60 channel whereby the head rest travels substantially in the locus of the occupant's head.

In testimony whereof I have signed my name to this specification in presence of 65 two subscribing witnesses.

FRANK E. CASE.
